Kenneth M. Cross

UNITED STATES PATENT OFFICE

165,326

LIGHTING FIXTURE

Kenneth M. Cross, Monrovia, Calif., assignor to Cross Lighting Company, Los Angeles, Calif., a corporation of California

Application November 13, 1950, Serial No. 12,959

Term of patent 7 years

(Cl. D48—23)

To all whom it may concern:

Be it known that I, Kenneth M. Cross, a citizen of the United States, residing at Monrovia, county of Los Angeles, State of California, have invented a new, original, and ornamental Design for a Lighting Fixture, of which the following is a specification, reference being had to the accompanying drawing, forming a part hereof.

Fig. 1 is a top plan view of a lighting fixture, showing my new design;

Fig. 2 is a side elevational view thereof; and
Fig. 3 is a bottom view thereof.

I claim:

The ornamental design for a lighting fixture, as shown.

KENNETH M. CROSS.
